UNITED STATES PATENT OFFICE

JAMES D. DYER, OF KANSAS CITY, MISSOURI

WINDOW-SCREEN HANGER

Application filed February 23, 1929. Serial No. 341,994.

My invention relates to improvements in window screen hangers.

One of the objects of my invention is to provide novel means for hanging a screen frame in a window frame, which is simple, cheap, durable, strong, not liable to get out of order, which is adapted for application to a screen frame of ordinary type, and to window jambs provided with usual screen frame engaging pins. My invention provides further a novel hanger member by the use of which a screen frame can be swung outwardly and upwardly to and releasably retained in an upwardly and outwardly inclined reversed position.

The novel features of my invention are hereinafter fully described and claimed.

In the accompanying drawing, which illustrates the preferred embodiment of my invention,

Fig. 1 is an outside elevation of a screen frame provided with my improved hangers and shown mounted in its operative lowermost position in a window frame.

Fig. 2 is a view similar to Fig. 1, and partly broken away, in which the screen frame is shown in the reversed upwardly and outwardly inclined position, in which it is releasably held by my improved hangers.

Fig. 3 is a view similar to Fig. 1, the screen frame being shown lifted so as to disengage the pivot pins from the hanger members, so as to release the screen to enable its removal.

Fig. 4 is an enlarged section on the line 4—4 of Fig. 1.

Fig. 5 is an enlarged section on the line 5—5 of Fig. 2.

Fig. 6 is a perspective view of one of my improved hangers, enlarged.

Fig. 7 is an enlarged vertical sectional view of a corner portion of the screen frame and a part of the adjacent hanger.

Similar reference characters designate similar parts in the different views.

My improved screen hanger, in its preferred form, as shown, comprises a member, such as a metal plate, which is provided with an end portion 1, a vertical end portion 2, and a middle inclined portion 3 in which is provided a longitudinal slot 4, the upper end

of which is preferably extended into the vertical portion 2, as shown in Fig. 6.

5 designates a usual screen frame slidably mounted between two window jambs 6, below two pivot pins 7 which respectively project inwardly from the jambs 6 at the outer sides of two stops 8 mounted respectively in the jambs 6.

Two of the hanger members are mounted on the screen frame 5, the portions 1 being fastened, as by screws 9 to the upper end of the screen frame, as shown. The inclined portions 3 of the hangers extend respectively upwardly toward the jambs 6 adjacent thereto, and the vertical portions 2 are disposed respectively adjacent to the jambs 6 at the outer sides of the stops 8.

When the screen frame is in its lowermost and operative position, as shown in Fig. 1, the pins 7 extend respectively through the slots 4, thus holding the screen frame 5 in its operative position. The hanger members pivotally engage the pivot pins 7 at the upper ends of the slots 4, so that the screen frame 5 can be swung upwardly and outwardly to a reverse position, and then moved slightly downwardly, to the position shown in Fig. 2, in which position, the vertical portions 2 of the hanger members will engage respectively the outer sides of the stops 8, thereby releasably holding the screen frame in such reverse position, and holding it from swinging downwardly therefrom.

To release the screen frame 5 from the reversed position, shown in Fig. 2, the frame is lifted slightly until the pins 7 bear against the ends of the slots 4, the frame is then swung downwardly to the closed position, Fig. 1, in which position it can be fastened releasably by a hook 10 on the screen frame. 90 The hook 10 is adapted to releasably engage, in the usual manner, a screw eye 11 mounted in the sill of the window frame.

To remove the screen from the window, the frame is lifted until the pins 7 pass out of the slots 4, Fig. 3, when the screen frame 5 may be bodily outwardly removed.

As is shown in Figs. 1, 2, 3 and 7, the horizontal portions 1 of the hangers, respectively extend across the joints between the ends of

the top rail and the stiles of the screen frame 5, and each horizontal portion 1 is provided with two holes through which respectively extend two screws 9, which screws respectively extend into the top rail and the adjacent stile of the screen frame. By this construction, the hanger serves, in addition to the functions already described, to tightly bind together the top rail and the stiles of the 10 screen frame.

By providing each hanger with the inclined middle portion 3 having the slot 4, either hanger is adapted for use at either the right or left position on the screen frame, so that 15 the hangers do not have to be furnished in pairs of rights and lefts.

The provision of the inclined portion with the slot 4 has a further advantage in that moving the screen frame lengthwise entirely 20 frees the hanger from the pin 7 and permits the screen to be moved directly bodily outwardly from the window frame, when the screen is in either the position shown in Fig. 3, or when in the reverse position, shown in 25 Figs. 2 and 5.

I do not limit my invention to the structure shown and described, as modifications, within the scope of the appended claims, may be made without departing from the spirit 30 of my invention.

What I claim is:—

1. In window screen hangers, a hanger member having an end portion adapted to be fastened horizontally on the upper end of a 35 screen frame vertically slidably against a window jamb and against a stop on the inner side of said jamb and below a pin inwardly extending from said jamb, said hanger member having a portion inclining upwardly toward said jamb, when the hanger member is affixed to the screen frame, said inclined portion having a longitudinal slot adapted to receive therethrough said pin, when said screen frame is in its lowermost position, said pin 40 being adapted to pass out of said slot when said frame is lifted to a predetermined position, to release the frame, said member pivotally engaging said pin to permit said frame to swing upwardly to an upwardly and outwardly inclined reversed position, said hanger member in such reversed position of the frame being adapted to engage said stop and hold said frame from downwardly swinging. 45

2. In window screen hangers, a hanger member having an end portion adapted to be fastened horizontally on the upper end of a screen frame vertically slidable against a window jamb and below a pin inwardly extending from said jamb, said hanger member having a portion inclining upwardly toward said jamb, when said screen frame is in operative position, said inclined portion having a longitudinal slot through which said pin extends, when said screen frame is in its lowermost position, said pin being adapted 50

to pass out of said slot when said screen frame is lifted to a predetermined position, so as to release said screen frame.

3. In window screen hangers, a hanger member having a horizontal portion adapted to be fastened to the upper end of a screen frame slidably mounted against a window jamb below a pin extending inwardly from said jamb, said hanger member having a portion inclining upwardly from said horizontal portion toward said jamb, and having a longitudinal slot in said inclined portion adapted to have extended therethrough said pin, when said screen frame is in its lowermost position, said pin passing out of said slot when said screen frame is lifted to a predetermined position, so as to permit the release of said screen frame, said hanger member being adapted to pivotally engage said pin at the upper end of said slot to permit said screen frame to swing outwardly and upwardly. 75

4. In window screen hangers, in combination with a screen frame slidably mounted between two jambs of a window below two pins which respectively extend inwardly from said jambs, of two hanger members having respectively two horizontal portions fastened to the upper end of said screen frame, and provided each with a portion which inclines upwardly toward the adjacent jamb, and which is provided with a longitudinal slot adapted to have extended therethrough the adjacent one of said pins, said pins being adapted to pass out of said slots when said screen frame is lifted to a predetermined position, so as to release said screen, said hanger members being adapted for pivotal movement on said pins, to permit said screen frame to swing outwardly and upwardly. 90

In testimony whereof I have signed my name to this specification.

JAMES D. DYER.
